UNITED STATES PATENT OFFICE.

LEVI F. KNODERER, OF COLUMBUS, OHIO.

GAS-BURNER.

SPECIFICATION forming part of Letters Patent No. 732,193, dated June 30, 1903.

Application filed February 9, 1903. Serial No. 142,478. (No model.)

To all whom it may concern:

Be it known that I, LEVI F. KNODERER, a citizen of the United States, residing at Columbus, in the county of Franklin and State of Ohio, have invented a certain new and useful Improvement in Gas-Burners, of which the following is a specification.

This invention relates to gas-burners, and has for its object to provide an improved device of this character which is especially adapted for use in connection with ordinary heating and cook stoves, furnaces, and other gas and oil consuming heaters. It is furthermore designed to have the device complete in itself and to provide the same with means for supporting it within the fire-box without altering or changing the latter in any manner whatsoever.

Another object is to provide for adjustably supporting the device with respect to the grate and also for adjusting the burner properly with respect to the air-mixer in order that the entire device may be accommodated to the conditions of each and every individual fire-box.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a vertical sectional view of a gas-burner embodying the features of the present invention and applied in operative position with respect to a fire-box. Fig. 2 is a cross-sectional view taken on the line 2-2 of Fig. 1, and Fig. 3 is a detail perspective view of the ring for adjustably supporting the device upon the grate.

Like characters of reference designate corresponding parts in each and every figure of the drawings.

As hereinbefore indicated, it is an essential object of this invention to arrange the device for application to a stove, and in order that this application may be clearly understood there has been shown in the accompanying

drawings a portion of a fire-box or fire-pot 1 and an ordinary grate 2; but it will of course be understood that the form of these common or ordinary parts may be considerably varied without interfering with the present device.

One embodiment of the present invention, as shown in the drawings, consists of a cylindrical mixer 3, which is open at its top and bottom and is provided at its lower end with crossed bars 4, preferably extending diametrically across the mixer and provided at intermediate points with one or more laterally-enlarged portions having openings therein, 55 which are surrounded by upstanding annular flanges 5. While two such cross-bars are shown, it will of course be understood that one or more than two may be employed. Through each flange 5 extends a set-screw. 60 It is preferable to have each cross-bar provided with terminal ears 7, which are boited or riveted to the walls of the mixer 3, as best shown in Fig. 1.

The seats 5 are designed to receive the 75 burners proper, two of which have been indicated at 8. Each of these burners projects above and below the adjacent cross-bar and is connected to a supply-pipe 9 and is held rigidly in place by the adjacent set-screw 6, 80 and is therefore capable of being adjusted vertically through the seat 5.

At the top of the mixer 3 are suitable lugs or projections 10, which rise from the upper edge of the mixer and are designed to support a baffle-plate 11, which rests loosely upon the lugs and is of a greater diameter than the mixer, so as to project in all directions beyond the external periphery thereof.

Embracing the middle portion of the mixer 90 3 is a supporting-ring 12, which is formed in duplicate half-sections, the inner marginal edge of each section being provided with an upstanding rim 13, that snugly embraces the mixer. A set-screw 14 pierces the rim and engages the mixer, so as to connect the former to the latter. The abutted ends of the ring-sections are provided with diametric upstanding flanges 15, as best shown in Fig. 3 of the drawings, and these flanges are pierced by 95 suitable bolts 16, so as to connect the ring-sections.

In fitting the present device to a fire-pot, as shown in Fig. 1 of the drawings, the cen-

tral grate-bars are removed and a flat metallic ring or plate 17 is placed upon the remaining grate-bars and surrounding the opening produced by the removal of the central bars. The ring 12 is supported upon the plate 17, and the mixer 3 is supported within and upon the flange 13 by means of the set-screws 14 and can be adjusted vertically, according to the conditions of any particular application. The purpose of the plate 17 is to close the openings between the grate-bars and around the mixer in order that all air must pass upwardly through the mixer instead of around the same. When in use, the flames and products of combustion rise into contact with the baffle-plate 11 and then spread radially outward between the upper edge of the mixer and the baffle-plate and into contact with the walls of the fire-box, thereby heating the latter in an effective manner.

From the foregoing description it will be understood that the device of the present invention is complete in itself and may be applied to any ordinary fire-box or fire-pot without altering or changing the same in any manner whatsoever beyond removing such grate-bars as may be necessary to accommodate the mixer 3.

Having thus described the invention, what is claimed, and desired to be secured by Letters Patent, is—

1. A device of the character described, comprising an open-ended tubular mixer, a burner supported within the mixer, a supporting-flange embracing the mixer, and set-screws carried by the flange and engaging the mixer to adjustably support the latter within the flange.

2. A device of the character described, comprising a tubular open-ended mixer, a burner supported within the mixer, an external annular supporting-ring embracing the mixer and substantially L-shaped in cross-section, and set-screws piercing the upstanding member of the ring and engaging the mixer and adjustably supporting the latter within the ring.

3. A device of the character described, comprising an open-ended tubular mixer, a burner supported within the mixer, a sectional external annular supporting-ring embracing the mixer, and means for detachably connecting the sections of the ring.

4. A device of the character described, comprising a tubular open-ended mixer, a burner supported within the mixer, an external annular ring embracing the mixer and

formed in sections provided with corresponding flanges, and fastenings engaging the flanges and detachably connecting the ring-sections.

5. A device of the character described, comprising a tubular open-ended mixer, a burner supported within the mixer, an external annular supporting-ring embracing the mixer and substantially L-shaped in cross-section, said ring being formed in sections with the abutted ends of the sections provided with corresponding flanges, fastenings detachably connecting the flanges, and set-screws piercing the upstanding member of the ring and engaging the mixer to adjustably support the latter within the ring.

6. A device of the character described, comprising an open-ended tubular mixer, a cross-bar within the mixer and provided with an opening, an annular flange surrounding the opening, a burner adjustable endwise through the opening, and a set-screw piercing the flange and engaging the burner to adjustably support the latter.

7. A device of the character described, comprising an open-ended tubular mixer, an open-work burner-support within the mixer and provided with flanged open-ended burner-seats, burners adjustable endwise within the seats, and set-screws piercing the flanges and engaging the burners to adjustably support the latter.

8. A device of the character described, comprising an open-ended tubular mixer, a supporting-ring intermediately embracing the mixer, set-screws carried by the ring and engaging the mixer to support the latter within the ring, a burner-support within the mixer and provided with an open-ended burner-seat, a burner adjustable endwise through the seat, and a set-screw carried by the burner-support and engaging the burner to adjustably support the latter.

9. The combination with a fire-pot and the grate thereof having its central grate-bars removed, of a ring-shaped plate surrounding the opening in and supported upon the grate, an open-ended tubular mixer located in the opening formed by the removal of the grate-bars, a supporting-ring embracing the mixer and resting upon the ring-shaped plate, the latter closing the annular space between the mixer and the walls of the fire-pot, and a burner within the mixer.

LEVI F. KNODERER.
